UNITED STATES PATENT OFFICE.

THOMAS J. BYRNE, OF BROOKLYN, NEW YORK

DOLL.

Application filed December 10, 1926. Serial No. 152,774.

This invention relates to dolls and particularly to an improved head and body structure for dolls; and the object of the invention is to fashion the head and neck portion of a doll from a body of rubber, preferably hollow, which is so molded or otherwise formed as to bring out the characteristics and features of the face including the eye, ear, nose and mouth characteristics, the body of rubber employed being of such nature and strength as to normally retain the proper shape of the head even when subjected to inward pressures, or to assume shape when pressed inwardly; a still further object being to provide the crown of the head with a recess for receiving and supporting a hair or wig pad in connection with which the natural or artificial hair is mounted; a further object being to construct the head of the doll of a rubber, preferably of a flesh tint or color, the eyes, eye-brows, mouth and cheeks being tinted to represent, as near as possible, natural appearances; a still further object being to provide the body portion of the doll, including the arms and legs, with an enclosing casing or jacket of rubber, molded or otherwise formed to fit comparatively snugly upon the limbs and body of the doll, said body covering being also preferably composed of rubber of a flesh tint; a still further object being to provide a body covering of the class described including hands and feet portions composed of solid rubber; and with these and other objects in view, the invention consists in a doll of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a doll made according to my invention.

Fig. 2 is an enlarged sectional view of the head portion of the doll; and,

Fig. 3 is a front and sectional view of the doll seen in Fig. 1.

In practice, I provide a doll body structure which may be composed of any desired material and constructed in accordance with standard and well known methods, comprising a body portion 5 with which are mov-

ably coupled arms 6 and legs 7. The joint of the arms with the body at 8 is constructed in any desired manner as well as the joint of the legs with the body at 9. The forearms 6^a are also jointed at the elbows as seen at 10, while knee joints 11 are also provided.

At the top of the body portion 5 is a slight upwardly projecting neck portion 12. It will be noted that the forearms and calves terminate in blunt ends 13 and 14 respectively, in other words, are not provided with the usual hands and feet, customary in the construction of dolls of conventional form. Mounted upon the body portion of the doll, including the arms and legs, is an enclosing casing or jacket 15 preferably composed of rubber. The casing or jacket is molded or otherwise formed to the contour of the doll body and includes arm portions 16 and leg portions 17. The arm portions terminate in hands 18, preferably composed of solid rubber, while the legs terminate in feet 19, also preferably composed of solid rubber. The top of the casing 15 is provided with a neck opening 20 which is sufficiently large to permit of the passage of the legs, arms and body therethrough when extended, the elasticity of the casing permitting of such extension. It is also preferable that the casing or jacket 15 be composed of a rubber of a flesh tint or color, and if desired, the hands and feet may be characterized to natural representation.

I also employ a head member 21 composed of rubber, and which in the construction shown is hollow and formed by molding or otherwise, the periphery of the member 21 being shaped or molded to form the characteristics of the nose 22, eyes 23, mouth 24 and ears 25. The head member 21 is also preferably formed of rubber of a flesh tint of color, to give a natural representation, and the eye-brows, eyes, lips as well as cheeks may be tinted or colored to bring out, as near as possible, a natural life-like appearance.

The thickness of the wall of the head member 21, and the nature of the rubber employed will be such as to maintain the facial features and contour, and general shape of the head, even when subjected to inward pressure, and if indented in such pressures, the same will return to natural position. In the construction of the head member 21, it is preferred that the crown portion of the

head, and extending to the back of the head, be provided with a recess 26 in which is mounted a pad or strip 27. The pad or strip 27 contains the hair 28 for the head of the 5 doll, the hair being imbedded in and constituting part of the strip or sheet 27, and said strip may be glued, cemented or otherwise adhered to the head member 21 as will be apparent.

10 The head member 21 extends downwardly in a neck portion 29 which terminates in a chest and shoulder portion 30 which fits upon the body portion 5 of the doll and around the extended neck 12 thereof. The lower 15 edges 31 of the head member 21 or the portion 30 thereof are tapered and overlap the upper edge of the covering or casing 15 around the neck opening 20 to form a neat and finished appearance. The head member 20 21 may be secured to the body of the doll in any desired manner, for example, by gluing or cementing the head 21.

With my improved doll construction, it will be apparent that a doll of substantially 25 natural appearance will be produced, as well as one which may be kept clean and sanitary at all times. It will also be apparent that the several joints of the limbs of the doll are covered, and thus present a better and 30 more natural appearance than jointed dolls as heretofore constructed, and the hands and feet will present a soft and natural effect rather than the stiff, hard hands and feet commonly employed. Further, by virtue of 35 the structure of the entire doll, the same becomes literally non-breakable, it being understood that the casing or covering 15 may be composed of comparatively heavy rubber, and the body, including the arms 40 and legs may be of a non-breakable material.

It will also be understood that while I have shown and described certain details of construction for carrying my invention into 45 effect, that I am not necessarily limited to these details, and various changes in and modifications of the construction herein shown and described may be made within the scope of the appended claims without 50 departing from the spirit of my invention or sacrificing its advantages.

Having fully described my invention, what I claim as new and desire to secure by Letters Patent, is:—

55 1. A doll comprising a body portion including arms and legs, and a casing, or

jacket formed independent of said body and composed of elastic material and adapted to be mounted upon said body, said casing or jacket including arm and leg portions, and 60 hands integral with said casing.

2. A doll comprising a body portion including arms and legs, and a casing or jacket formed independent of said body and composed of elastic material and adapted to be 65 mounted upon said body, said casing or jacket including arm and leg portions, and hands and feet integral with said casing.

3. A doll comprising a body portion including arms and legs, and a casing or jacket 70 formed independent of said body and composed of elastic material and adapted to be mounted upon said body, said casing or jacket including arm and leg portions, and hands and feet integral with said casing, 75 and said hands and feet being composed of solid rubber.

4. The combination with a doll body having jointed arms and legs, of a casing enclosing 80 said body and the arms and legs, said casing being formed independent of said body and composed of resilient material and including solid hands and feet.

5. The combination with a doll body having jointed arms and legs, of a casing enclosing 85 said body and the arms and legs, said casing being formed independent of said body and composed of resilient material and including solid hands and feet, and a hollow head formed independent of the casing and 90 characterized to represent natural features, said head being composed of resilient material and adapted to be mounted on and secured to the body of the doll.

6. The combination with a doll body having jointed arms and legs, of a casing enclosing 95 said body and the arms and legs, said casing being formed independent of said body and composed of resilient material and including solid hands and feet, and a hollow 100 head formed independent of the casing and characterized to represent natural features, said head being composed of resilient material and adapted to be mounted on and secured to the body of the doll, and a wig 105 pad imbedded in and secured to the crown of said head.

In testimony that I claim the foregoing as my invention I have signed my name this 7th day of December, 1926.

THOMAS J. BYRNE.
